ATHLETIC IMPLEMENT AND METHOD OF
MAKING THE SAMEWilliam G. Curry, Springfield, Mass., assignor, by
mesne assignments, to A. G. Spalding & Bros.
Inc., a corporation of Delaware

Application November 25, 1938, Serial No. 242,403

4 Claims. (Cl. 273—81)

The invention relates to improvements in golf clubs or other athletic implements and in the method of making the same, and more particularly to the construction of the grip portion 5 of the golf club or athletic implement, and the method of manufacture and assembly thereof.

An object of the invention is to provide a grip construction and method which will result in economy of material and labor used in making 10 the same.

Another object is to provide a construction which will reduce or eliminate strain on the material thereof.

A further object is the provision of a grip 15 construction in which complete cementing of the grip material to the foundation is readily obtained.

Another object is to provide simplicity of 20 construction of grip material and foundation with close adherence and conformation to the latter.

Other objects will appear hereinafter, the invention comprising the features, combination and arrangement of parts and steps as herein- 25 after shown and described and particularly pointed out in the claims.

In the drawings, illustrating one embodiment of the invention,

Figure 1 is a plan view of a panel grip member for a golf club according to the invention, 30 prior to its application to the foundation.

Fig. 2 shows the assembly of the foundation member of the golf club grip portion to the grip panel in flat condition.

Fig. 2a is an end view of the same from the right of Fig. 2.

Fig. 3 is a side view of the assembly with the panel grip member wrapped on the foundation.

Fig. 3a is an end view of the same from the 40 right of Fig. 3.

Fig. 4 is a plan view of the panel grip assembled to the foundation after trimming off excess of the panel.

Fig. 4a is an end view of the same from the 45 right of Fig. 4.

Fig. 5 is a plan view of the finished panel grip and Fig. 5a is a view of the right end of Fig. 5.

Fig. 6 is a sectional view substantially centrally of the finished grip of Figs. 5 and 5a in 50 position, to be grasped by the player with the ridge and seam on the under side and the flat face on the back side of the grip.

Fig. 7 is a view showing the operation of forming the grip panel around the foundation, 55 the position of the club and grip being indi-

cated in dotted lines in the punch press constituting the forming fixture.

Fig. 8 is a view showing the operation of trimming off the excess leather left after the operation of forming the grip.

Fig. 8a is a detail view in end elevation.

Fig. 9 is a view of the cap assembly of the grip.

Fig. 10 is an enlarged fragmentary cross-sectional view of Figure 5 showing the construction of the margins of the cover panel at the 10 seam on an enlarged scale.

Referring to the drawings, the invention comprises providing a strip or sheet of material 1, which desirably may be of leather material, of greater width than that necessary to wrap exactly about the foundation 2 of the golf club grip portion, so that an excess is provided. The foundation 2 is preferably of generally tapered form to correspond with the tapered shape of the shaft 3, and may desirably be of molded cork and rubber composition or of paper primed with cement.

The strip or panel grip member 1, which may be perforated or not as desired, after being split to the required thickness and skived as shown at 4, and coated with preferably rubber cement, is assembled with the shaft and foundation laid substantially centrally thereon and also desirably coated with rubber cement, as shown in Figs. 2 and 2a, preferably with the rib or ridge-like portion 5 of the underside of the foundation disposed substantially uppermost, which ridge portion may desirably be provided, although the invention is not restricted thereto as a plain concentric foundation may be used.

The panel grip member 1 is wrapped about the foundation and the excess portions of the width of the strip are brought together in the form of a flange 14 extending substantially radially in respect to the foundation, as shown in Figs. 3 and 3a, with the excess material pressed together so as to unite from their edges to a point at or closely adjacent the surface of the tapered foundation.

The excess material is then trimmed off with the result as shown in Figs. 4 and 4a, and the edges of the leather material left by the trimming operation are pressed down upon the foundation so that they will form a substantially flush joint or seam as seen in Figs. 5 and 5a.

The grip may then be wrapped with tape which may be done in a grip winding machine and preferably cured to cure the cement. The curing may be done in an electric oven at about 68°—70° C. for about 1½ hours.

The grips may then be removed from the oven, the wrapping of tape removed, and the seams desirably may be sanded lightly as with a sanding cone to remove roughness.

- 5 A cap is then applied to the end of the shaft and grip, which cap may desirably be of rubber and preferably of a form as shown having a hollow stem of a diameter to be received within the hollow shaft, and a cap portion which extends across the end of the hollow shaft and having a flange which fits down against the outside of the upper end of the hollow shaft.

The foregoing is a brief description of the assembly, the details of the several operations involved being more fully described hereinafter.

If the foundation is of paper, it is desirably applied with the club in a winding machine and without removing the club from the winding machine, cement may be applied with a brush, and the club removed from the machine, placed on a truck and allowed to dry.

The paper foundation as thus prepared, or the cork and rubber foundation, either of which may desirably be employed, may then preferably be primed with a coat of a preferably vulcanizable rubber cement, and allowed to dry without curing prior to the assembly operation with the panel grip member 1. The foundation may be of substantially round shape and preferably tapered, but desirably may be form shaped as for example in James V. East application No. 23,497, filed May 25, 1935, and known as the Jones Form Grip, and embodying a ridge on the under side and a flattened face on the rear side of the grip, as seen in Fig. 6.

In preparing the panel grip members 1 for assembly with the foundation, the leather hides, which preferably are the material employed, are cut into strips the width of which is equal to the length of the grip desired, say 12, 13, 14 or 15 inches. Steel patterns of a length of fifteen inches having a width at one end of about $3\frac{1}{8}$ " and at the other end of about $2\frac{1}{2}$ " may be used with sharp shoe knives in cutting the grips. Shorter panels may be cut in the same die, the width at the bottom changing with the length. The grips are cut from the strips by reversing the pattern after each cut so as to cut as many grips as possible from the strips. It is not essential that the panels be tapered as they may have substantially uniform width although the taper is desirable for the sake of economy in providing a grip panel for a tapered foundation. Irregular ends and small pieces may be cut into panels with little waste and with economy of material. This economy of material is not possible with methods of cutting spiral grips employed heretofore, which not only cannot use scrap or small pieces of leather as may be used by the present invention, but in cutting spiral grips it has been necessary to reject the soft stretchy leather. In cutting the panel grips according to the present invention substantially all of the leather may be used.

65 The panel grips 1 may be used either plain or they may be perforated, as desired. The grip members 1 may be perforated in a perforating machine provided with suitable guides. The rows of perforations 25 extend along the grip panel and the perforations of one row are preferably staggered with respect to the perforations in an adjacent row. The perforations are preferably disposed in two groups or sections of three rows each, each group being respectively substantially parallel to its adjacent edge of the

panel, so that the groups of rows of perforations taper generally with the edges of the panel. With the grain side up and the wider end of the panel toward the operator, the center of the first row of holes on the right may desirably be about $\frac{1}{2}$ " from the right edge of the panel, and the center of the first row of holes on the left may be about $\frac{5}{8}$ " from the left edge of the panel. The rows of each group may desirably be uniformly spaced apart from about $\frac{1}{4}$ " to $\frac{3}{8}$ ", with a similar space between the two groups at the small end of the panel widening toward the wide end of the panel. Guides in the machine are set to give the desired distances of the perforations from the edges of the panel and the panel is put through the perforating machine with the grain side up and first with the wide end toward the machine using one guide and then with the narrow end towards the machine using another guide.

An alternative and desirable method of cutting and perforating the grip panels comprises feeding the strips, cut from the hides by hand, into a punch press equipped with a cutting and perforating die, keeping the middle of the strip 25 in the middle of the die. The pedal on the punch press is then pressed to cut and perforate two panel grips at one stroke of the press. The operation is repeated. Small pieces or ends of leather may be cut by hand into proper sized grips which 30 can be perforated if desired on the punch press. For plain unperforated grips a blank cutting die is provided.

After cutting the grip panels and perforating if desired, the grips are preferably split to desired thickness, which may be about .04 in. for men's grips and about .033 in. for ladies' grips.

The grip panels may then be immersed in a solution of suitable grip dressing for about $\frac{1}{2}$ hr. at room temperature (80° F.) and thereafter 40 removed from solution and allowed to drain. They may then be wiped with a cloth dampened with naptha and spread individually on galvanized screen trays and allowed to dry until there is no odor of solvent from the grips. The grips are 45 then preferably skived at their lower or narrow end edges for later application of Celluloid collar, and cement is applied to the under side of the panel grips, which are then ready for assembly with the foundation. The cement is preferably a vulcanizable rubber cement or the like.

In the assembly, the grip panels may desirably be placed, cement side up, in a line-up jig, and a club provided with the foundation is placed in the jig so that a predetermined mark on the 55 shaft registers with the lower edge of the grip panel. The face of the club head is preferably pressed against a suitable stop, and the foundation is then pressed down upon the grip, substantially as illustrated in Figs. 2 and 2a.

If the grip is perforated, it is preferably lined up with the club so that the center line of the blank space between the sections or groups of perforations, is in the vertical plane through the center line of the shaft when the club is soled 65 against the ground. This brings the seam on the under side of the grip, and may be employed whether the foundation is of plain tapered shape or form shaped, the seam in the latter case being disposed adjacent the longitudinal rib on the 70 under side of the grip and desirably on the forward side thereof. On clubs having plain unperforated panel grips, and form shaped foundations, as for example in East application No. 23,497 above referred to, the grip may desirably 75

be lined up so that the seam will come on the side opposite to or remote from the flattened face on the foundation and sufficiently under the shaft so that when viewed from above when the club 5 is grounded, the seam will not be visible. On all plain rounded grips, the grips are preferably lined up so that the seam will come directly under the shaft when the club is grounded.

The club is then removed from the line-up jig 10 and after inserting a short rod in the upper end of the shaft to serve as a temporary handle, the club is preferably grasped with the right hand holding the short rod and the left hand holding the lower part of the shaft, and the back of the 15 grip panel is pressed firmly against the rubber forming sheet 6 in a punch press 7, as shown in Fig. 7, the curved or slightly hollowed part of the grip near the enlarged upper end being disposed against the one-inch rubber strip 8 near the right 20 end of the larger sheet 6. The forming sheet may desirably be cut from rubber or other flexible material of about $\frac{1}{4}$ " by means of a pattern of desired size, and is disposed in the punch press between the upper and lower forming plates 9 25 and 10 thereof. The forming sheet is secured at its upper portion to the plate 9 by bar 28 and at its lower portion is removably secured to the lower plate 10 by means of bar 29 and screws 30. A back plate is shown at 11 against which the 30 forming sheet bears, and the press head and press bed plate are indicated at 12 and 13.

The operating pedal of the press is then pressed sufficiently for the press to punch twice to bring the two marginal portions of the grip 35 panel firmly and evenly together as seen in Figs. 3 and 3a. The club may then be removed from the forming press and the short rod may be removed from the shaft. The rubber strip 8 may desirably be cut from about $\frac{1}{8}$ " stock and be approximately one inch wide and six inches long, 40 with its upper end fastened as shown and its lower end free. It is desirable to lubricate the rubber forming sheet occasionally with hand soap at places where the sheet rubs against the metal 45 parts of the press.

The club is desirably then placed on the trimming fixture or press as illustrated in Figs. 8 and 8a, and the leather lip or flange 14 resulting from the forming operation is inserted between the upper and lower knives 15 and 16 with the top end of the grip substantially even with the end of the knives, as shown. The grip is pressed firmly against the knives with the lip 14 extending between the knives. The operating 55 pedal (not shown) is then preferably pressed twice, as two cuts or bringing together of the knives are desirable in order to insure a clean job of cutting. The trimming press is indicated generally by the numeral 17 and embodies a 60 table 18, top and bottom plates 19 and 20 carrying the knives, with a spring 21 at each end between the plates, suitable guide posts 22 and bushings 23 being also provided. Guide faces, as 65 shown at 19a and 20a are also provided for engagement by the club.

As indicated in Fig. 3a the inner side faces of the marginal portions of the grip panel 1 are engaged with each other, as a result of the forming or enfolding operation, to a point at or closely adjacent to the surface of the grip foundation. The trimming having been effected, as described, 70 at the junction of the flange 14 with the grip proper, the result is substantially as shown in Figs. 4a and 5a, in which the raw edges 1a of the panel face outwardly, and lie in a plane or

planes other than radial of the grip, while the inner side faces of the marginal edge portions 1b are turned outwardly from the foundation to a substantially radial position and desirably abutting substantially as shown.

After the trimming the club is removed from the trimming press and passed to an operator, who rolls down the seam, as with a hand roller, to the condition substantially as shown in Fig. 5a. The grip is then wrapped with tape, desirably by putting the club in a grip winding machine, the tape being tightly wrapped on the grip, preferably beginning at the upper end of the grip and extending spirally down the length of the grip just to the lower end of the grip.

With an electric oven preferably maintained at a temperature of about 68°-70° C., the grip is desirably placed in the oven and cured for approximately 1½ hrs. to cure the cement, whereupon the grip is removed from the oven 20 and allowed to cool and then the tape wrapping is removed.

The seam of the grip is then desirably sanded lightly as with a sanding cone to remove roughness.

Next a cap is applied to the end of the shaft and grip. The cap may preferably be formed of rubber having a hollow stem 24 to be received within the hollow shaft 3 of the club, with an integral cap portion 26 covering the end of the 30 shaft and grip foundation 2, and having a flange 26a which fits down against the outside of the upper end of the hollow shaft which extends above the grip foundation. The upper end of the hollow shaft is thus embraced inside and out by 35 the cap. The cap is desirably made substantially larger in diameter than the upper end of the grip and is then trimmed or sanded to reduce it in diameter to make a flush abutment with the grip proper.

Following the capping operation, a Celluloid collar is preferably applied to the bottom of the grip over the skived portion, the grip may be wiped with a cloth dampened with naphtha to remove dirt, cement, etc. which may have been 45 picked up during manufacture. The seam and other spots which require coloring may be dyed with a suitable coloring solution applied with a small swab, the excess dye wiped off the grip, and any marks, rough or high places on the grip may 50 be smoothed out with a small burnishing rod or wooden arm-roller.

The invention results in an absence of strain on the leather or other material used for the grip, and in absence of strain on the foundation material, since the sheet material is laid around the foundation in being applied thereto without such strain as takes place in wrapping material spirally around the grip foundation with requisite tightness according to the practice heretofore. 55 A complete and uniform cementing of the foundation and leather panel surfaces is obtained by the present invention as distinguished from the intermittent cementing resulting from the spiral wrapping method, and a more closely and well defined shaping in accordance with the base shape, such as the form shaped grip of East application No. 23,497 and known as the "Jones Form Grip," is obtained by the present invention 60 as distinguished from the spiral wrapping. Also no wood plug and tacks are necessary with the panel grip of the present invention, as are needed for anchorage of ends of the spirally wrapped on grip. Labor economy in the grip- 65 70 75

ping operation is a distinct advantage of the invention.

The foregoing description applies to a golf club grip for a right handed player and the necessary reversal construction and dimensions in applying the invention to a left handed grip will be readily apparent.

In the case of a spiral grip the operator has to pull rather hard on the long piece of leather 10 in wrapping it on in a spiral smoothly to get as tight and smooth a seam as possible. This stretches the leather and to make it still worse, the leather stretches more in some places than in others. Where the spiral grip is perforated 15 the rows of holes therefore may be stretched relatively wide apart in some places and closer together elsewhere. Also the perforations may retain their round punched shape in some places and may be pulled into elliptical shape in other 20 places. By the present panel grip assembly, the distortion and strain incident to the spiral type of grip is avoided.

The invention, while described particularly in connection with a golf club, is not limited thereto, as it will be apparent that it may be applied 25 to other athletic implements having a grip portion, such, for example, as a racket for tennis or the like.

I claim:

30 1. In an athletic implement grip having a grip foundation on the shaft of the implement and a sheet or panel of material covering the foundation in an adhesive union therewith, with the marginal portions of the panel adjoining, the 35 said marginal portions of said covering panel being turned or bent outwardly with their inner

side faces disposed opposite each other inner side face to inner side face and in an adhesive unsewn union, and said marginal portions having raw edge faces substantially at the outer surface of the tubular panel, said raw edge faces facing outwardly of the grip and lying in a plane or planes other than radial of the grip and forming a substantially flush continuation of the outer surface of the tubular grip panel. 5

2. Steps in a method of applying hand grips to 10 the handle foundations of athletic implements, comprising en folding an elongated panel of sheet material transversely into tubular shape around the handle foundation in such width of material as to provide excess marginal portions, and cementing the material to the foundation, turning the marginal portions outwardly in a substantially radial direction forming flanges extending lengthwise of the handle, uniting the turned marginal flanges solely by cementing them together 15 inner side face to inner side face to an innermost point substantially at the surface of the foundation, and trimming off the cemented marginal flanges substantially flush with the outer surface of the tubular grip so formed. 20

3. Steps in a method according to claim 2 including smoothing the outwardly facing raw edges remaining after trimming off of the flanges substantially flush with the outer surface of the tubular grip, to provide a smooth finish to the 30 grip. 25

4. Steps in a method according to claim 2 in which the cement employed is vulcanizable, and subjecting the applied grip to vulcanization.

35

WILLIAM G. CURRY.
